(57) **CLAIM**

The ornamental design for a computer connector housing, as shown and described.

DESCRIPTION

A portion of the disclosure of this design patent document contains material to which a claim of copyright protection is made. The copyright owner has no objection to the facsimile reproduction of the patent document or the patent disclosure as it appears in the U. S. Patent and Trademark Office file or records, but reserves all other rights.

FIG. 1 is a perspective view of a computer connector housing, in accordance with the present invention.

FIG. 2 is a top view thereof.

FIG. 3 is an underside view thereof.

FIG. 4 is a side view thereof.

FIG. 5 is a corresponding side view thereof.

FIG. 6 is a rear view thereof; and,

FIG. 7 is a frontal view thereof.

The broken lines showing the printer connector environment in the Figures are for illustrative purposes only and form no part of the claimed design.
